UNITED STATES PATENT OFFICE.

HERMANN WAGNER, OF HOCHST-ON-THE-MAIN, GERMANY, ASSIGNOR, BY MESNE ASSIGNMENTS, TO GENERAL ANILINE WORKS, INC., OF NEW YORK, N. Y., A CORPORATION OF NEW YORK.

MANUFACTURE OF AZO DYESTUFFS DERIVED FROM 2-HYDROXYNAPHTHALENE-3-CARBOXYLIC-ACID-ARYLAMIDES.

No Drawing. Original No. 1,622,690, dated March 29, 1927. Serial No. 544,613, filed March 17, 1922.
Application for reissue filed February 21, 1929. Serial No. 341,833.

According to U. S. Patent No. 1,034,853 of Winter et al. granted August 6, 1912, dyestuffs of good properties are obtained by the combination of diazo-compounds with arylides of the 2,3-hydroxynaphthoic acid. Now it has been found that dyestuffs of surprisingly favorable properties are obtained by the combination of diazo compounds derived from mononuclear aromatic amines with o-toluidides of 2,3-hydroxynaphthoic acid. The compounds containing halogen and among these the compounds containing halogen in both components are distinguished by their excellent fastness properties.

The new azo dyestuffs are represented by the general formula:

wherein R may be a mononuclear aromatic residue, and X may be hydrogen, halogen, or another monovalent substituent. Upon reduction with stannous chloride and hydrochloric acid an aromatic amine and a toluidide of 1-amino-2-hydroxy-3-naphthoic acid are produced.

An advantage of these dyestuffs as compared with the anilido and nitranilido compounds of 2,3-hydroxynaphthoic acid as well as with the compounds cited in great number in the U. S. Patent No. 1,034,853 consists in that they have a great kier-boiling and a much better discharge ability so that a remarkably good white is obtainable. Moreover, the new dyestuffs possess a very pure shade. As compared with the compounds of other toluidides of 2,3-hydroxynaphthoic acid, those of the o-toluidides show besides other at least equally good properties in numerous cases a better fastness to light. But the special importance of this invention resides in the discovery of a field of use for o-toluidine and o-nitrotoluene respectively. This substance is formed, as it is known, as the chief product by nitrating toluene. For the homologues occurring in small quantity

especially p-nitrotoluene great domains of utilization are known already, whereas for the chief substance, the o-nitrotoluene, there has been only a small demand so that it presented a disagreeable waste-product in the chemical industry. Therefore, the discovery of a group of dyestuffs, having such excellent fastness properties and at the same time providing a use for this product, is of very great importance.

Manifestly, the fastness properties of the above-described azo dyestuffs derived from 2-hydroxynaphthalene-3-carboxylic acid-aryl amides will to some extent be determined by what mononuclear aromatic residue is selected to occupy the position R, and by what monovalent substituent is selected to occupy the position X, of the above general formula. Since an object of the present invention is to provide dyestuffs of good fastness properties, it is to be understood that the mononuclear aromatic residue R, and the monovalent substituent X, of the general formulæ hereinbefore set out and appearing in the appended claims exclude such substituted mononuclear aromatic residues, and respectively, such monovalent substituents, as are known to tend to depreciate the fastness properties of azo dyestuffs.

However, it is a remarkable fact that in some cases even such dyestuffs as contain a nitro group as a substituent can be rendered more fast to kier-boiling when using as coupling component an ortho-toluidide or a halogenated ortho toluidide of 2,3-oxynaphthoic acid.

Examples.

1. The material is padded with a solution of: 20 g. 2,3-hydroxynaphthoic acid-o-toluidide, 60 g. caustic soda solution of 22° Bé., 20 g. para soap PN, made up to 1 liter.

Then it is dried and printed with the following color: 15.2 g. 6-nitro-2-toluidine, 200 cc. water, 24 cc. hydrochloric acid of 22° Bé., 95 mix well to a paste, cool with 150 g. ice, then add 8 g. sodium nitrite dissolved in 50 g. water, 550 g. tragacanth (60:1000) and to this are added before using: 20 g. sodium acetate; total, 1 kg.

The dyestuff has the following structural formula:

2. The material is padded with a solution of: 20 g. 2,3-hydroxynaphthoic acid-o-toluidid, 60 g. caustic soda solution of 22° Bé., 20 g. para soap PN, made up to 1 liter.

15 Then it is dried and printed with the following color: 12.7 g. p-chlor-anilin, 200 g. water, 24 c. c. hydrochloric acid of 22° Bé., mix well to a paste, cool with 150 g. ice, then add 8 g. sodium nitrite dissolved in 50 g. water, 550 g. tragacanth (60:1000) and to this are added before using: 20 g. sodium acetate; total, 1 kg.

20 The dyestuff has the following structural formula:

3. The material is padded with a solution of: 20 g. 2,3-hydroxynaphthoic acid-4-chloro-toluidid ($\text{CH}_3:\text{NH}:\text{Cl}=1:2:4$), 65 g. caustic soda solution of 22° Bé., 20 g. sodium ricinolate, made up to 1 liter.

40 Then it is dried and printed with the following color: 16.8 g. 4-nitro-o-anisidin are dissolved with 30 cc. hydrochloric acid of 22° Bé. and 200 cc. boiling water, well cooled and then added 150 g. ice. To this is added while stirring 7.2 g. sodium nitrite dissolved in 50 cc. water. The solution is made up with water to 500 g.

45 This diazo solution is mixed with 480 g. tragacanth (60:1000) and to this are added before using: 20 g. sodium acetate crystallized; total 1 kg.

50 Thus is obtained a very bright red on the fibre of very good fastness properties.

The dyestuff has the following structural formula:

4. The material is padded with a solution of: 27 g. 2,3-hydroxynaphthoic acid-4-brom-o-toluidid, 60 g. caustic soda solu-

tion of 22° Bé., 20 g. para soap PN, made up to 1 liter.

Then it is dried and printed with the following color: 15.7 g. p-chloranisidin, 200 g. water, 24 cc. hydrochloric acid of 22° Bé., mix well to a paste, cool with 150 g. ice, then add 8 g. sodium nitrite dissolved in 50 g. water, 550 g. tragacanth (60:1000) and to this are added before using: 20 g. sodium acetate; total, 1 kg.

75 The dyestuff has the following structural formula:

5. Padding liquor: 23 g. 2,3-hydroxynaphthoic acid-5-chlor-o-toluidid, 60 g. caustic soda solution 22° Bé., boiling water, 90 20 g. para soap PN, to 1 liter.

90 Printing paste: 17.5 g. 4-chlor-3-toluidine hydrochloride, 200 g. water, 16 g. hydrochloric acid of 22° Bé., dissolve, cool with 150 cc. ice, then add 7 g. sodium nitrite dissolved in 50 g. water, 540 g. tragacanth (60:1000) and before use add 20 g. sodium acetate; total, 1 kg.

95 The dyestuff has the following structural formula:

110 Instead of 17.5 g. 4-chlor-3-toluidine the same quantity of 4-chlor-o-toluidine for instance can be used.

6. The yarn is prepared with the following solution: 12.7 g. beta-hydroxynaphthoic acid-o-toluidid, 20 cc. caustic soda solution of 34° Bé., 30 cc. sodium Turkey red oil 115 50%, 500 cc. hot water, with cold water made up to 1 liter.

120 The printed yarn is wrung and dyed with the following diazo-compound: 17.5 g. 4-chlor-o-toluidine hydrochloride are dissolved with 16 cc. hydrochloric acid 22° Bé. and 200 cc. boiling water, then cooled while adding 150 g. ice. To this is added a solution of 7.2 g. nitrite in 50 c. c. water while stirring. The solution is made up to 4 liters 125 and to this added 20 g. sodium acetate before use.

130 After dyeing, it is well wrung, rinsed and soaped. Thus is obtained a very bright red of excellent fastness properties.

The dyestuff has the following structural formula:

7. The diazo-compound obtained from 14.1 g. chlor-o-toluidine in the usual manner is poured in an aqueous suspension of 29 g. 2,3-hydroxynaphthoic acid-o-toluidide prepared by dissolving it in caustic soda solution and again precipitating it with diluted acetic acid. The dyestuff separates in bluish-red flakes; then is filtered, washed and dried.

20 The dyestuff has the following structural formula:

I claim:

30 1. As new products the water-insoluble azo dyestuffs of the general formula:

wherein R represents a mononuclear aromatic residue, and X represents hydrogen, halogen or another monovalent substituent.

40 2. As new products the water-insoluble azo dyestuffs of the general formula:

50 wherein R represents a mononuclear aromatic residue and X represents hydrogen or halogen, one X being halogen and the other X being hydrogen.

55 3. As new products the water-insoluble azo dyestuffs of the general formula:

wherein R represents a mononuclear aromatic residue.

4. As new products the water-insoluble azo dyestuffs of the general formula:

wherein Y represents hydrogen, halogen or alkyl, one Y being halogen, a second Y being alkyl and the other Y's being hydrogen, and wherein X represents hydrogen or halogen, one X being halogen and the other X's being hydrogen.

5. As new products the water-insoluble azo dyestuffs of the general formula:

wherein Y represents hydrogen, halogen or alkyl, one Y being halogen, a second Y being alkyl and the other Y's being hydrogen, and wherein X represents hydrogen, or halogen, one X being halogen and the other X being hydrogen.

6. As new products the water-insoluble azo dyestuffs of the general formula:

wherein Y represents hydrogen, halogen or alkyl, one Y being halogen, a second Y being alkyl and the other Y's being hydrogen.

7. As new products the water-insoluble azo dyestuffs of the general formula:

wherein Y represents hydrogen or halogen,

one Y being halogen, and the other Y's being hydrogen, and X represents hydrogen or halogen, one X being halogen and the other X's being hydrogen.

5. As new products the water-insoluble azo dyestuffs of the general formula:

wherein Y represents hydrogen or halogen, one Y being halogen, and the other Y's being hydrogen, and wherein X represents hydrogen or halogen, one X being halogen and the other X's being hydrogen.

9. As new products the water-insoluble azo dyestuffs of the general formula:

wherein Y represents hydrogen or halogen, one Y being halogen and the other Y's being hydrogen.

10. As new products the water-insoluble azo dyestuffs of the general formula:

wherein Y represents hydrogen or halogen, one Y being halogen, and the other Y being hydrogen, and wherein X represents hydrogen or halogen, one X being halogen and the other X's being hydrogen.

11. As new products the water-insoluble azo dyestuffs of the general formula:

wherein Y represents hydrogen or halogen, one Y being halogen, and the other Y being hydrogen, and wherein X represents hydrogen or halogen, one X being halogen and the other X being hydrogen.

12. As new products the water-insoluble azo dyestuffs of the general formula:

wherein Y represents hydrogen or halogen, one Y being halogen, and the other Y being hydrogen.

13. As new products the water-insoluble azo dyestuffs of the general formula:

wherein X represents hydrogen or halogen, one X being halogen and the other X's being hydrogen.

14. As new products the water-insoluble azo dyestuffs of the general formula:

wherein X represents hydrogen or halogen, one X being halogen and the other X being hydrogen.

15. As new products the water-insoluble azo dyestuffs of the general formula:

In testimony whereof I affix my signature.

HERMANN WAGNER.
